TOY VEHICLE

Arthur R. Thomas, Detroit, Mich.

Application July 25, 1939, Serial No. 287,302

4 Claims. (Cl. 280—1.19)

This invention relates generally to vehicles and more particularly to toy vehicles.

It is an object of the present invention to provide a novel child's toy vehicle from which fun, and at the same time healthful exercise are derived.

Another object of the present invention is to provide a rocking horse vehicle which when the horse is rocked causes locomotion of the vehicle giving the general sensation of riding a real horse.

Other objects of the invention reside in the particular construction and arrangement of parts of the device as shown in the accompanying drawings in which—

Figure 1 is a side elevational view of the toy;

Fig. 2 is a top plan view of the toy;

Fig. 3 is a view taken transversely of the toy substantially along the line 3—3 of Fig. 1;

Fig. 4 is a cross sectional view showing certain details of construction of the toy and taken along the line 4—4 of Fig. 1;

Fig. 5 is a cross sectional view showing certain details of construction of the toy and taken along the line 5—5 of Fig. 1;

Fig. 6 is a cross sectional view showing certain details of construction of the toy and taken along the line 6—6 of Fig. 1;

Fig. 7 is a cross sectional view showing certain details of construction of the toy and taken along the line 7—7 of Fig. 1, and

Fig. 8 is a cross sectional view showing certain details of construction of the toy and taken along the line 8—8 of Fig. 1.

Referring to the drawings by characters of reference, the toy rocking horse operated vehicle shown, includes a frame 10 supported on front and rear wheels 11 and 12 respectively, these wheels preferably being provided with rubber tires for easy operation. The frame 10 includes a pair of longitudinal frame members 13, 14 which are flat upright members, spaced apart and rigidly secured together by cross members 15, 16, 17, 18, 19 and 20 which are arranged at spaced intervals along the length of the frame and may be secured thereto by bolts and nuts or by other suitable means. As is more clearly shown in Fig. 8, the rear wheels 12 are mounted on a rotatable axle 21 which extends through aligning clearance apertures in the frame members 13, 14, which are supported by a pair of oppositely extending rigid brackets 22. Inwardly of each of the rear wheels 12 is a bearing 23 in which the axle 21 is freely rotatable, these bearings 23 respectively abutting the inner faces of

the wheel hubs thus holding the wheels in proper spaced relation on the axle 21. The upper ends of the brackets 22 are apertured to fit respectively over the bearings 23 which are externally threaded to receive nuts 24 which rigidly secure the brackets and their respective bearings together.

As shown in Fig. 2, the rear wheels 12 are held in proper alignment, relative to the frame 10, by brackets or braces 22^a which are of general V-shape having their inner spaced ends rigidly secured respectively to the frame members 13 and 14. The legs of each of the V-shaped braces 22^a converge outwardly and join in a flattened portion which is provided with an aperture to receive the bearings 23 to which the braces 22^a are rigidly secured by the nuts 24. One of the rear wheels 12 is fixed to the axle 21, as at 25, to rotate therewith, this wheel being the driving wheel and the other wheel is preferably free on the axle.

Mounted on the axle 21, and fixed thereto in any suitable manner between the longitudinal frame members 13, 14, is a wheel 26 driven by a V-belt 27 from a drive wheel 28. Mounted on the frame, a roller 27^a, in engagement with the belt 27, may be provided and be bodily movable in any suitable manner to tighten or loosen the belt 27, as desired. The drive wheel 28 is rotatably supported by a stub shaft 29, mounted in a plate 30 which is rigidly secured to the frame member 13 inwardly thereof, see Fig. 7.

Mounted on the frame between and parallel with the frame members 13, 14 is an operating member or lever 32 which may be in the form of a rocking horse which is operable by rocking the same to drive or give locomotion to the vehicle. The member 32 is mounted on the frame in a manner such that in operation, the member or horse 32 has a moving fulcrum giving a forward and backward movement, as well as, a rocking movement to the horse. To this end, the member 32 is supported by a pair of front rocker arms 33 and a pair of rear rocker arms 34, the arms of each pair being arranged on opposite sides of the horse or rocker member 32. The arms 33, 34 are pivoted at their upper ends to the rocker member 32 and are pivoted at their lower ends to the side frame members 13, 14, the upper pivot points of the rocker arm being closer together than the lower pivot points thereof and the arms 33 preferably being shorter in length than the arms 34, as shown in Fig. 1. The provision of a moving fulcrum for the horse, giving the horse a slight forward and rearward movement gives to

the rider somewhat the sensation of riding a real horse, and I have found that by making the front arms 33 shorter than the rear arms 34 that the action of the horse is easier than is the case if the arms are of the same length. In order to steady the horse, or limit side movement thereof, a pair of guide braces 35 are provided, one on each side of the horse, and these braces are pivotally connected at their lower ends to the frame side members 13, 14 respectively, above the arms 33, 34 and near the top of the frame members. The lower ends of the guide braces 35 may be pivotally connected to the side frame members by pins 36, secured in and to the frame members, these pins 36 projecting inwardly and being provided with spacer members 37 which space the bracket 35 from the inner wall surfaces of the frame members, as shown in Fig. 4. The upper ends of the braces are slotted as shown to receive opposite end portions of a pin or bolt which is secured in and extends through the member 32, the bolt having threaded end portions to receive nuts for retaining the braces in place.

A pair of plate members 39, rigidly secured, one to each side of the horse, depend therefrom providing an extension, and extending between and pivoted to the lower ends of the plate members is one end of a connecting rod or link 40, the other end of the link having a bearing 41 to rotatably receive a crank pin 42 which is secured in and to the drive wheel 28 offcenter thereof. A seat 43 may be rigidly secured on the member 32 adjacent the rear end thereof and suitably located foot rests 44 may be rigidly secured, one to each of the frame side members 13, 14 outwardly thereof. It will be seen, that a rider may by force of his weight rock or pivot the horse in a clockwise direction, Fig. 1, which will pull the link or rod 40 forward, rotating wheel 28 which through the belt 27 will drive wheel 26 and axle 21 to rotate the rear ground drive wheel thus, giving locomotion to the vehicle.

Connected to the operating member or horse 32, on the opposite side of the fulcrum thereof from the seat 43 is one end of a helical coil spring 45, the other or lower end of the spring preferably being attached to one end of a turnbuckle 46 which is anchored to a bracket 47, secured to the frame cross member 16. For best results, the spring 45 is arranged at an angle with the lower end thereof arranged rearwardly of the upper end. When the horse is rocked in a clockwise direction, Fig. 1, by weight of the rider on seat 43, the spring 45 is tensioned and when the rider rises and places his or her weight on the foot supports 44, the force of spring 45 acting on the horse through rockers 33, 34, link 40, wheel 28, belt 27 drives the rear wheel 12 and rocks or pivots the horse in the opposite direction. Thus, it will be seen that application of a person's weight pivoting member 32 in a clockwise direction, Fig. 1, drives the vehicle and that such movement tensions spring 45 which upon being released by the rider exerts its force for also driving the vehicle and in so doing rocks the horse in a counterclockwise direction. The position of the horse or operating member 32, shown in the drawings is an intermediate position substantially midway between the extreme upper and lower positions. If desired, for heavier persons a second spring 48 may be provided and one end of the spring may be attached to a belt connecting the rear rocker members 34 and the other end of the spring 75

may be attached to a turnbuckle 49 which may be anchored to the frame, as at 50, Fig. 1.

Referring now to the front wheel suspension of the frame and to the steering mechanism, as is more clearly shown in Fig. 3, the front wheels 11 are mounted for free rotation on an axle 52, spaced apart by a rigid cross member 53 which is located immediately below the axle 52 and provided with upturned end portions 54 which are apertured to receive the axle, the inner surfaces of the wheels hubs being spaced from the cross member upturned portions 54 by washers or spacer members 55. The frame extends between the axle 52 and the cross member 53, and the frame cross member 15 seats or rests on the cross member 53. The frame cross member 15 is a hollow rectangular member, as shown in Fig. 3 and within member 15 is provided a vertically extending hollow tube 56 aligning with apertures in the top and bottom of the cross member 15 to receive a bolt 57 about which the front wheel suspension pivots for steering the vehicle. At its upper end the bolt 57 extends through a plate-like suspension member 58 which pivots on the upper surface of the frame cross member 15, immediately below the axle 52, and is provided with upturned end portions 60 which are apertured to receive the axle 52, the vehicle frame being suspended from the axle 52 by the suspension member 58 and being supported by the wheel cross member 53.

A pair of extension plates 61 equally spaced on opposite sides of the bolt 57 are rigidly secured to the wheel cross members 53, such as by means of rivets 62, and project forward of the axle, as shown in Fig. 2. A pair of transversely extending plate-like arms 63 are rigidly secured at their outer ends as at 64, respectively to the forward ends of the extension members 61, the inner ends of the arms being pivotally connected together and to one end of a longitudinally extending plate-like push rod 65 by a suitable pivot pin which may be a bolt 66. The member 65 extends rearwardly of the vehicle and is pivoted intermediate its ends to the frame cross member 16, the bolt which holds the anchor bracket 47 of the spring 45 also serving as the pivot for the member 65, see Fig. 4. A T-shaped steering member or lever is pivoted, as at 68, to the frame cross member 18 to pivot substantially horizontally, and an arm 69 thereof extends forwardly and is provided with a slot which extends longitudinally of the arm 69 and receives a bolt 70 provided in the rear free end of the member 65 to permit the arm and lever to pivot. From the pivot 68 of the T-lever, oppositely disposed integral arms 71 extend outwardly, Fig. 2, and seating on each of the arms 71, adjacent the outer ends thereof is a U-shaped pivoted yoke or clevis 72 which may be pivotally connected to respective arms in any suitable manner. Pivoted to each clevis 72 is a link 73 which extend parallel and forward having their forward ends pivotally connected respectively to the lower ends of a pair of upright steering levers 74 which are provided with reinforcing members 75, see Fig. 5, and are pivoted respectively to the frame members 13, 14, as at 76. On their upper ends, the steering levers 74 are provided with horizontally extending handles 77 for convenience of steering and these handles also serve to aid the riders to retain their balance in the up and down motion required to operate the vehicle. It will be seen that in steering the vehicle when one of the

levers 74 is pushed forward the other is moved rearward and vice-versa.

While I have herein shown and described in detail, a toy vehicle for children in which the rocking of a member imparts locomotion to the vehicle, it will readily be understood that the rocking member need not necessarily be in the form or pictured as a horse and that various other changes may be made without departing from the spirit or scope of the invention which is to be limited only by the appended claims.

What I claim is:

1. A toy vehicle comprising, a frame including a pair of longitudinal frame members mounted on ground engaging wheels, a rockable member disposed between and extending longitudinally of said frame members, a pair of spaced arms on each side of said rockable member, each pair of arms having upper ends pivoted to said rockable member and having lower ends pivoted to said frame members, means acting to rock said rockable member in one direction, a seat on said rockable member on which a person may sit and rock said member, drive means for the rear ground wheels, and means operatively connecting said rockable member and said drive means.

2. A toy vehicle comprising, a frame including a pair of longitudinal frame members mounted on front and rear ground engaging wheels, a rockable member disposed between and extending longitudinally of said frame members, a pair of spaced arms on each side of said rockable member and disposed intermediate the ends thereof, said arms having upper ends pivoted to said rockable member and having lower spaced ends pivoted to said frame members, means acting to rock said rockable member in one direction, said rockable member having a seat on which a person may sit to rock said rockable member in the opposite direction, drive means for the rear wheels of the vehicle, and means operatively connecting said drive means and said rockable member.

3. A toy vehicle comprising, a frame including a pair of longitudinal frame members mounted on front and rear ground engaging wheels, a rockable member disposed between and extending longitudinally of said frame members, a pair of spaced arms on each side of said rockable member and disposed intermediate the ends thereof, said arms having upper ends pivoted to said rockable member and having lower spaced ends pivoted to said frame members, means acting to rock said rockable member in one direction, said rockable member having a seat on which a person may sit to rock said rockable member in the opposite direction, crank means for the rear wheels, and a connecting rod having one end connected to said crank means and having its other end connected to said rockable member intermediate the arms of said pair of arms.

4. A toy vehicle comprising, a frame including a pair of longitudinal frame members mounted on front and rear ground engaging wheels, a rockable member disposed between and extending substantially parallel with said frame members, a pair of spaced arms on each side of said rockable member, said arms having upper ends pivoted to said rockable member and having lower ends pivoted to said frame members, spring means anchored to and adjacent the front end of said frame and connected to said rockable member forwardly of said arms, said spring means being operable to rock said rockable member in one direction, said rockable member having a seat on which a person may sit and rock said rockable member in the opposite direction, spring means anchored to said frame and connected to the rear arms intermediate the ends thereof, said second spring means acting to rock said rockable member in said one direction, drive means for the rear wheels, and means operatively connecting said drive means and said rockable member.

ARTHUR R. THOMAS.
